UNITED STATES PATENT OFFICE.

ROY SAUNDERS, OF ST. LOUIS, MISSOURI, ASSIGNOR TO SAUNDERS MOTOR POWER COMPANY, OF EAST ST. LOUIS, ILLINOIS, A CORPORATION OF ILLINOIS.

ROTARY ENGINE.

1,271,950.

Specification of Letters Patent.

Patented July 9, 1918.

Application filed March 12, 1917. Serial No. 154,271.

To all whom it may concern:

Be it known that I, ROY SAUNDERS, a citizen of the United States, residing at the city of St. Louis and State of Missouri, have invented a new and useful Rotary Engine, of which the following is a specification.

This invention relates to rotary engines. Specifically, the present invention has reference to a rotary engine of the type disclosed in my Patent 1,236,009, Aug. 7, 1917.

The engine comprises a stationary cylinder, and a rotor operatively mounted within the cylinder, and provided with a series of piston chambers in which the pistons are mounted. Within the cylinder the controlling mechanism for the piston is arranged, whereby the piston is moved to and from position of compression, the movement of the pistons being essentially across a radial line from the axis of the rotor through the pivots of the pistons.

An object of the invention is to provide an improved mechanism for controlling the operation of the pistons in a rotary engine of the type mentioned, comprising an axially movable actuating part operatively engaging each shaft or pivot of the pistons; whereby axial movement of said actuating parts will effect movement of the pistons to and from positions of compression by moving the pistons across the radial lines from the axis of the cylinder intersecting the pivots of the pistons, as mentioned above.

With the foregoing and other objects in view, I have produced a rotary engine of the novel construction, combination and mode of operation as hereinafter described and claimed.

In the accompanying drawings, in which I have illustrated an appropriate form of my present invention Figure 1 is a longitudinal sectional view of the rotor, and the piston actuating appliances. Fig. 2 is a transverse sectional view on the line 2—2 of Fig. 1. Fig. 3 is a sectional view on the line 3—3 of Fig. 2, illustrating the cam by which the piston actuating parts are controlled. Fig. 4 is a transverse sectional view of the rotor and cylinder on the line 4—4 of Fig. 1.

The engine in which I have shown the present invention embodied comprises a stationary cylinder 1, the heads of which support bearings for the rotor shaft 2. The

rotor 3 is attached to the shaft 2, and is provided with a series of piston chambers in each of which a pivoted piston 4 is mounted.

Each of the pistons 4 is in the form of a leaf attached at its inner edge to a shaft 5. The shafts 5 are journaled for rocking movements in anti-friction bearings 6 supported by the end walls of the rotor. The shafts 5 are parallel with the rotor driven shaft 2, and it is by rocking the shafts 5 that the pistons are moved to and from positions of compression.

At one end of the motor the shafts 5 are extended toward the head of the cylinder and the extremities of said shafts are journaled in anti-friction bearings 7 carried by a sleeve 8 attached to and rotating with the shaft 2. The extended portion of each of the shafts 5 is formed with spiral grooves 9, with which the shafts actuating parts engage in order to rock the shafts as an incident to rotation of the rotor. In the embodiment illustrated, the shafts actuating device comprises, for each shaft, a sleeve 10 slidably mounted on the shaft, and having recesses for the keys operating within the grooves 9. The keys 11 are mounted in recesses in the parts 10, and engage in the grooves 9 so that when the parts 10 are reciprocated axially, the shafts 5 will be rocked, it being understood that the parts 10 are prevented from rocking. Parts 10 are held from rocking movements by spherical keys 12 mounted in grooves in a sleeve 8, and engaging in complementary grooves 14 in the members 10. The grooves are of sufficient length to permit axial movement of the parts 10 in opposite directions as required to rock the shafts 5.

Each of the parts 10 has a rigid projection 15, carrying a roller 16. The rollers 16 of the members 10 operate within a cam passage, formed between a member 17 and a similarly shaped member 18, spaced from the member 17. The two members 17 and 18 are bolted together by bolts 19 and have interposed plates 20, which may be reduced or increased in number as required to adjust the two members 17 and 18 accurately. The cam thus constructed is supported in rigid connection with the head of the cylinder by an extended portion 21 of the member 18, the same being secured to the cylinder.

der head by bolts 22. The bearing 23 of the shaft 2 is mounted within the cylindrical portion 21.

A cylindrical partition wall 24 is attached to the rotor, and operates upon or against a supporting member 25, carried by the extended portion 21 on one of the cam members.

By reference to Fig. 1, it will be observed that the rotor is wholly out of contact with the cylinder in which it is mounted, thus entirely eliminating friction between said parts. The rotor being spaced from the cylinder permits the water to circulate entirely around the rotor, and into the chamber between the cylinder and the cylindrical partition 24. The partition 24 forms an impervious joint with the member 25 so that the water cannot pass the partition wall. The chamber within the partition wall 24 constitutes an oil chamber, and as is readily apparent by reference to Fig. 1, the oil may pass between the end wall of the rotor and the adjacent cam members and enter the spaces within which the shafts 5 are extended. In this way all of the operating parts of the piston controlling mechanism are thoroughly lubricated, and the oil is free to circulate against all of said parts.

By reference to Fig. 3, the construction and form of the cam passage within which the rollers 16 operate will be readily understood. As illustrated, the cam passage is adjacent to the rotor at two diametrically opposite points, and is at a considerable distance from the rotor at two diametrically opposite points. Said cam is symmetrically shaped so that each actuating member 10 will be moved twice in each direction at each revolution of the rotor. This mode of operation applies to all of the pistons.

The mechanism described is absolutely positive and accurate in its operation and wholly dispenses with the use of levers and links in the actuating mechanism. The parts are all of strong construction, and will more efficiently control the pistons than the usual link and lever mechanism.

It will be understood that the construction and arrangement of the various parts of the invention may be varied without departing from the principle of the invention or from the general mode of operation. I do not restrict myself to unessential features or details of the device, but what I claim and desire to secure by Letters Patent is:

1. In a rotary engine, a rotor, a series of rock shafts carried by the rotor, pistons attached to said shafts respectively, an axially movable member on each of said shafts, means for reciprocating said members axially as the rotor rotates, and means for rocking said shafts by the movement of said members.

2. In a rotary engine, a rotor, pistons

mounted in the rotor, a shaft for operating each piston, a member on each of said shafts for axial movement, means for reciprocating said members axially as the rotor operates, and devices whereby said members will rock said shafts as an incident to axial movement of said members.

3. In a rotary engine, a rotor, pistons mounted in the rotor, a shaft for operating each piston, a sleeve upon each of said shafts, means for reciprocating said sleeves axially upon the shafts as the rotor rotates, and operative connections between said sleeves and said shafts respectively for rocking said shafts as an incident to rotation of the rotor.

4. A rotary engine comprising a rotor, pistons mounted in the rotor, a rock shaft attached to each piston for operating the same, a sleeve mounted for axial movement upon each shaft, a cam for moving said sleeves axially on said shafts as an incident to rotation of the rotor, means for preventing said sleeves from turning relatively to their own axes as they are operated with the rotor, and a key connection between each sleeve and the shaft on which it is mounted whereby axial movement of the sleeve will turn the shaft while the sleeve is held from turning.

5. In a rotary engine, the combination with the piston actuating rock shafts of the rotor, of a sleeve mounted for axial movement upon each of said rock shafts, a cam, means whereby said cam will reciprocate said sleeves axially upon said shafts when the engine operates, and a connection with each sleeve and the shaft on which it is mounted whereby axial movement of the sleeve will rock the shaft.

6. In a rotary engine, the combination with a rotor, pistons mounted in the rotor, and shafts for moving the pistons, said shafts being provided with spiral grooves, of a sleeve mounted upon each shaft for axial movement, a key in connection with each sleeve engaging in the spiral groove in the shaft, and a cam for reciprocating said sleeves respectively as an incident to rotation of the rotor.

7. In a rotary engine, the combination with a rotor, pistons mounted in the rotor, and shafts for operating the pistons and having spiral grooves therein, of a sleeve mounted for axial movement on each shaft, a spherical key in each sleeve engaging in the groove in the shaft, a cam, and a projection on each sleeve operating on the cam for reciprocating said sleeves upon said shaft, as an incident to rotation of the rotor.

8. In a rotary engine, a rotor, pistons mounted in the rotor, shafts journaled in the rotor for rocking movements and being connected with the pistons respectively, an axially reciprocating member mounted on

each shaft, a cam for reciprocating said member as an incident to rotation of the rotor, an operative connection between each member and the corresponding shaft for 5 rocking said shaft as an incident to movement of said member, and a chamber for lubricant surrounding said parts.

9. In a rotary engine, the combination with a rotor, pistons in the rotor, rock shafts 10 for actuating the pistons and provided with spiral grooves, of a sleeve mounted for axial reciprocation upon each rock shaft, a

key movable by each sleeve in the spiral groove formed in the corresponding shaft, a cam, a projection on each sleeve, a roller 15 on said projection operating against the cam effectively to reciprocate the sleeve on said shaft as the rotor rotates, and an oil chamber adapted to contain a lubricant in which said parts operate.

In witness whereof, I have signed this specification.

ROY SAUNDERS.
